UNITED STATES PATENT OFFICE.

JOSEPH F. MONTINE, OF NEVINVILLE, IOWA.

RAIL-JOINT.

1,113,037.

Specification of Letters Patent.

Patented Oct. 6, 1914.

Application filed January 23, 1914. Serial No. 813,963.

To all whom it may concern:

Be it known that I, JOSEPH F. MONTINE, a citizen of the United States, residing at Nevinville, in the county of Adams and State of Iowa, have invented new and useful Improvements in Rail-Joints, of which the following is a specification.

The present invention relates to improvements in rail joints, and resides in the construction, combination and operative arrangement of parts set forth in the following specification and falling within the scope of the appended claims. The primary object of the invention is to provide a joint for two railway rails which will be comparatively simple in construction, cheap to manufacture, durable and thoroughly efficient in practice.

In the drawing: Figure 1 is a perspective view illustrating a rail joint constructed in accordance with the present invention, Fig. 2 is a horizontal sectional view on the line 2—2 of Fig. 3, and Fig. 3 is a transverse sectional view on the line 3—3 of Fig. 1.

Referring now to the drawing in detail, R—R designate two rails having abutting ends, the said rails being of the ordinary construction.

The numeral 2 designates the joint chair employed in connecting the rail ends. The joint chair 2 includes a base 3 upon which the rails rest, and is formed upon one of its sides with an angular inturned flange 4 which overlies the base and which receives the base flange of the rails. Integrally formed with the overlying flange 4 is a vertical flange 5, the same having its inner face channeled throughout its length, and the upper edge of said plate 5 is adapted to receive the underfaces of the rail heads. Formed integral with the plate 5, at the upper end thereof, is a longitudinally extending crest 6, the same inclining in opposite directions from the center thereof to its ends, and the central portion of the said crest is adapted to lie flush with the upper faces or tread portions of the rails, and is arranged at the meeting ends of said rails. The opposite side of the base 2 is formed with a vertically arranged longitudinally extending wall 7, the said wall having at its upper edge an inwardly and downwardly turned flange 8. The numeral 9 designates an angular brace member or angle bar for the rails, the same having its inner face

channeled throughout its length, and the said brace member being of a length corresponding with that of the joint chair. The angular flange 10 of the brace 9 is thicker at its longitudinal edge than at the remainder of the said brace, and the thickened portion provides an inclined wall or face 11 which is adapted to co-act with the inclined lower face of the flange 8 of the wall 7.

In arranging the rails upon the joint chair, I first position the rails within the chair, so that their flanges are received beneath the overlying flange 4 and are also engaged by the vertical plate 5 and the crest 6. To secure the rails in this position, I employ bolts 12 which pass through suitable openings in the vertical plate 5 and in the webs of the rails. If the channel of the plate 5 is not of sufficient depth, I recess the webs of the rails, as indicated by the numerals 13, the said recessed portions being shaped to agree with the shape of nuts 14 which are engaged by the bolts 12. To permit of the turning of the bolts I also recess the crest 6, as indicated by the numeral 15, and after the rails have been secured as just described, I slide the angular brace member 9 beneath the flange 8, and when the same is in proper position, I insert bolts 16 through suitable openings in the vertical plate of the brace member 9 which register with similar openings in the webs of the rails and in the vertical plate 5 of the chair, and I provide the said bolts with nuts 17. When the nuts 17 are screwed entirely home upon the bolts 16, the angle brace member 9 will be moved laterally toward the rails, which movement causes a tight frictional engagement between the angular faces or walls 11 of the member 9 and the underface of the flange 8 of the wall 7, and so effectively lock the brace member upon the rail chair and effectively prevent both lateral or longitudinal movement of the rails when the joint is complete.

From the above description, taken in connection with the accompanying drawing, the simplicity of the device as well as the advantages thereof will, it is thought, be perfectly apparent to those skilled in the art to which such invention appertains without further detailed description.

Having thus described the invention, what I claim is:

1. In a rail joint, the combination with

two rails having contiguous ends, of a joint chair including a base upon which the rails rest and having a side which embraces one of the faces of the rails, the base having its 5 other side provided with a vertically projecting longitudinally extending wall, the upper edge of which being formed with an inturned flange and the lower face of the flange being inclined downwardly an angular 10 brace, said brace being enlarged at the outer portion of its horizontal flange, the said upper face of the said enlargement being inclined, the brace member adapted to be inserted beneath the inturned flange of the 15 chair and upon the rails, means for connecting the brace with the rails and with the rail engaging portion of the joint chair, and said means adapted to slide the brace member to bring its flanged portion into tight 20 frictional engagement with the lower inclined face of the flange of the chair.

2. In a rail joint, the combination with two rails having meeting ends and the webs of the rails having openings, and said webs 25 having recesses upon one of their faces which surround certain of the openings, of a joint chair including a base upon which

the rails rest and having a side which is received within the fishing space at one side of the rails, the other side of the base being 30 formed with a vertical wall, the upper edge of which having an angularly disposed in-turned flange, bolts passing through openings in the first mentioned sides of the chair, nuts arranged within the recesses and engaging these bolts, an angular brace having its horizontal portion enlarged at its outer edge, the upper face of said enlargement being beveled, said brace adapted to be inserted over the webs of the rails beneath the flange of the vertical wall of the chair, the vertical member of the brace having openings which register with certain of the openings in the webs of the rails and with openings in the opposite side of the 45 chair, bolts passing through the openings, and nuts for the bolts.

In testimony whereof I affix my signature in presence of two witnesses.

JOSEPH F. MONTINE.
